Orn. W. Andrews of Providence R. I.
applier to

Isaac Bachus of Canterbury Conn & John Pitt Barstow of Norwich Conn.
Letters Patent No 505 Dated Sept 21st 1852

The schedule referred to in these Letters Patent and making part of the same

To all whom it may concern:

Be it known that J. O. W. Andrews of the City and County
of Providence and State of Rhode Island have invented a new ornamental design for booting stores
and I do hereby declare that the following is a full, clear and exact description of the same, reference

had
vning to the accompanying drawings forming part of this specification in which

Fig. 1 is a face view of one of the side plates of the stove with the doors attached.

Fig. 2 is a vertical profile section of the same in the line xx of Figure 1.

Fig. 3 is a face view of the back plate

Fig. 4 is a horizontal half section of the same in the line y of figure 3.

Fig. 5 is a face view of the upper front plate

Fig. 6 is a horizontal half section of the same in the line xx of Figure 5.

Fig. 7 is a face view of the lower front plate

Fig. 8 is a horizontal half section of the same in the line a of Figure 7.

Fig. 9 is a half transverse section of the top plate. Fig. 10 is a half transverse section of the bottom plate.

Fig. 11 is a side view of one of the feet. Fig. 12 is a half transverse section of the hearth plate.

Similar letters of reference indicate corresponding parts where they occur in the different Figures.

The side plates, of which one is in form precisely the reverse of the other except that in one there is a small door at A and the other is simply panelled at the corresponding part to imitate the said door. They are surrounded by a raised moulding B shown in profile in Figure 2. The doors are all surrounded by mouldings C and in the centre of each is a circular flower D from which rays E diverge in all directions nearly to the moulding C. There is also a raised panel surrounded by a moulding F nearly similar to C and the panel is ornamented by two circular bosses I from which there are diverging rays T. The back plate has a moulding similar to B before named along its top and bottom and another moulding F down each side. On the main flue there is a raised circular flower similar to D and from this flower rays similar to E diverge. On either side of the flue there is a raised ornament G.

The upper front plate has a moulding similar to B before named along the top and one similar to F down each side. The doors are of similar design to those on the side of the stove.

The lower front plate has mouldings similar to B and F before named along

3

Des 505

The top plate is surrounded by a moulding M. The bottom plate by a moulding N and the hearth plate by a moulding O. See their several profiles in sections. Figures 9, 10 and 11

The configuration of the feet is shown in figure 10.

What I claim and desire to secure by letter patent is

The design and configuration as herein shown of the above as a whole and
of the front, back, and side plates severally.
